UNITED STATES PATENT OFFICE.

WALLACE D. BOWIE, OF BOWIE, COLORADO.

LAMP-CLEANER.

1,126,372.

Specification of Letters Patent.

Patented Jan. 26, 1915.

Application filed April 28, 1914. Serial No. 834,921.

To all whom it may concern:

Be it known that I, WALLACE D. BOWIE, a citizen of the United States, and a resident of Bowie, in the county of Delta and State 5 of Colorado, have invented a new and Improved Lamp-Cleaner, of which the following is a full, clear, and exact description.

This invention relates to improvements in miners' lamps, and particularly to a cleaner 10 therefor.

The object in view is to provide an easily operated cleaner for the gas outlet pipe in miners' calcium carbide lamps.

Another object in view is to provide a 15 cleaning device easily applied and removed and also easily and quickly operated at any time for cleaning the gas outlet tube in lamps using calcium carbide.

In carrying out the objects of the invention a lamp of any desired kind may be provided or used. The lamp is provided with the usual gas outlet tubes carrying a burner structure provided with a small opening or tip through which the gas passes before it 20 is ignited. Associated with the gas tube and the tip are two members, namely, a retaining member and a needle connected with the retaining member. These are arranged so that the burner structure may be threaded 25 on to the retaining member and the needle may be extended through the gas outlet tip when the burner is screwed or turned until it occupies a predetermined position, whereby the gas outlet tip is cleaned.

30 In the accompanying drawings—Figure 1 is a side view of a miner's lamp with an embodiment of the invention applied thereto; Fig. 2 is a section through Fig. 1 approximately on line 2—2; Fig. 3 is a view 35 similar to Fig. 2 except that a retaining member is shown in section; Fig. 4 is an enlarged sectional view through Fig. 3 approximately on line 4—4.

Referring to the accompanying drawings 40 by numeral, 1 indicates a miner's lamp of any desired kind provided with a carbide reservoir 2 and a water reservoir 3. A water and gas tube 4 is also provided arranged in line with tube 5 in which a suitable wire 45 6 is placed designed to act in the usual manner for the cleaning of tubes 4 and 5, and also for better regulating the passage of water and gas. Arranged above the carbide chamber 2 is a gas chamber 7 into which

projects a tube 8. The tube 8 is designed to 55 accommodate the retaining member 9, and also the end of the reflector 10. The retaining member 9 is provided with a bifurcated portion 11 which is preferably somewhat resilient, and which is forced against tube 4 60 when the device is in operation. The bifurcated portion 11 merges into a tubular member 12 threaded exteriorly for receiving the interiorly threaded extension 13 of reflector 10. The tubular member 12 is formed with 65 an enlargement 12' which snugly fits the tube 8 so that the gas must pass through the tubular member as the same passes to the discharge outlet tip 14.

Arranged in the tubular extension 13 is a 70 gas outlet tip 14 having a comparatively small aperture 15 arranged therein through which the gas passes immediately previous to its ignition. In order to prevent the opening 15 from becoming clogged or 75 stopped up a needle 16 is provided which extends through the tubular part 12 of member 9, and is connected at 17 in any desired manner, as for instance by solder to member 9. The connection at 17 is preferably 80 such as to position needle 16 substantially central of the aperture 18 in tubular member 12. A bifurcated portion 11 is provided with shoulders 19 and 20 which snap over the inner ends of the tube 8 when member 9 85 is in operative position as shown in Figs. 2 and 3. This prevents a reverse movement of member 9 while the engagement of the ends of the bifurcated portion 11 prevents the rotation of member 11 together with the 90 tubular part 12.

In operation after the lamp has been properly filled reflector 10 is rotated until the end of needle 16 has left a sufficient opening in tip 14 to allow the proper amount of gas 95 to escape for producing the desired flame. If for any reason a particle of dirt or foreign matter should clog the opening 15 in the tip 14, reflector 10 may be rotated and thereby the tip 14 caused to telescope over 100 the needle, whereby the opening 15 will be cleaned. A reverse movement will bring the reflector back to its original position, whereupon the lamp may be again lighted. Under some circumstances, as for instance when 105 there is only a small amount of foreign matter in the opening or passageway 15 a slight back and forth movement of the reflector

will cause the foreign matter to be dislodged and the passageway may thus be cleaned without shutting off the gas entirely.

What I claim is—

- 5 1. In a device of the character described, means for producing a gas, a tube projecting into said means, a retaining member arranged in said tube, said retaining member being provided with an aperture there-
10 through, the exterior of said retaining member fitting against the interior walls of said tube so that the gas must pass through said retaining member, a needle arranged in the aperture of said retaining member and ex-
15 tending therefrom, said needle being an ap-
preciable size smaller than said aperture, a rotatable reflector threaded on to said re-
taining member, and an outlet tip rigidly
20 secured to the reflector, said outlet tip be-
ing provided with an aperture in line with
said needle, whereby when the reflector is
rotated in one direction said tip will tele-
scope over said needle, and when rotated in
25 the opposite direction will move from said
needle.
2. In a device of the character described, a lamp structure including means for the production of gas, a gas discharge tube ex-
tending into the casing of the lamp, a re-

taining member arranged in said tube and 30
fitting the same so that gas must pass
through said retaining member, said retaining
member being provided with a longitudi-
nal bore, and with a bifurcated end, said bi-
furcated end being formed with shoulders fit-
ting against the end of said tube, whereby the
retaining member is held in position, means
engaging said bifurcated end for preventing
said shoulder leaving said tube, a needle
40 connected with said retaining member and
extending through the bore therein, said
needle projecting beyond said retaining
member, a discharge tip provided with an
aperture in line with said bore, and a ro-
tatable member supporting said tip, said ro-
tatable member being threaded on to said
retaining member, whereby when the ro-
tatable member is moved the same will cause
the tip to move longitudinally of said needle
45 and the aperture therein to be cleaned 50
thereby.

In testimony whereof I have signed my
name to this specification in the presence of
two subscribing witnesses.
